CABINET

Philip Rosenberg, New York, N. Y.

Application January 3, 1942, Serial No. 425,495

7 Claims. (Cl. 45—77)

This invention relates to cabinets, more particularly to rotary cabinets in which partitioned sector-like drawers are mounted in sector-like drawer spaces of the cabinet.

Cabinets of the kind referred to are widely used in storerooms on land and sea. The present invention is useful in cabinets for either service, but it is of especial utility with reference to some of its features for service at sea where the cabinet becomes tilted with the rolling and pitching of the craft so that the drawers are apt to be hard to control when opened or are apt to slide open, and in that condition to become damaged, or to permit the contents of their compartments to become mixed or spilled.

The drawers when partially opened have been free to turn. This is highly objectionable because the location and the direction of unbalanced forces can shift suddenly.

It is an important object of the invention to provide means guiding each drawer for lengthwise movement, desirably along substantially the middle radius of the drawer, without turning. This stabilizes the direction of the forces to be contended against by anyone seeking to control an opened or partially opened drawer. It also opposes lateral unbalance and tends thereby to prevent sudden shifting of the load.

It has been the practice heretofore to provide aligned apertured lugs on the cabinet frame at the top and bottom of a tier of drawers, and to pass through the lugs and across the outer ends of the closed drawers a retaining pin which has been maintained in association with the cabinet frame by means of a chain or other flexible anchoring means. When it has become necessary to open one of the drawers of a tier, the other drawer or drawers of the same tier have necessarily become unlocked by withdrawal of the pin, and have had to remain unlocked until the opened drawer could again be closed. This has been a very serious drawback under some conditions, especially at sea in rough weather.

It is a further important object of the invention to provide a simple, efficient and economical means for individually locking every drawer so that there never need be any necessity for attempting to keep two or more free drawers under control at the same time.

Other objects and advantages will hereinafter appear.

In the drawings forming part of this specification

Fig. 1 is a view in elevation, broken away intermediate its ends for compactness of illustra-

tion, showing a rotary cabinet embodying the invention;

Fig. 2 is a fragmentary transverse sectional view taken on the line 2—2 of Fig. 1, looking in the direction of the arrows;

Fig. 3 is a perspective, fragmentary view illustrating a drawer partially withdrawn from the associated drawer space of the cabinet;

Fig. 4 is a fragmentary view in sectional elevation taken on the line 4—4 of Fig. 2, looking in the direction of the arrows; and

Fig. 5 is a fragmentary plan view, partly broken away, showing a drawer partly withdrawn from the cabinet.

The illustrative embodiment of the invention consists of a rotary cabinet 1 which comprises a base 2 and a vertical shaft 3. The cabinet desirably comprises a series of cabinet sections, or of cabinet and bin sections, mounted with capacity for rotation independently of one another upon the shaft 3. Since all features of the invention are embodied in a single cabinet section, however, Fig. 1 has been broken away for compactness of illustration and only a single cabinet section 4 has been illustrated.

The cabinet section 4 is rotatably mounted upon the shaft 3 in any suitable manner. As illustrated, the frame of the cabinet section 4 comprises a sleeve 5 having a flanged ring 6 secured to the inner face thereof. The ring 6 bears upon a ball bearing 7, and the ball bearing in turn bears upon a ring 8. The ring 8 is supported by the ends of a pin 9 which transfixes the shaft 3.

The cabinet section 4 comprises a supporting platform 14 which is separated into sectors by permanent dividers 14a. The dividers 14a are connected by welding to the platform 14 and to the sleeve 5. The platform is provided with a short, upstanding, circumferential flange 14b.

Each sector is adapted to receive a drawer-space-defining, sector-like frame section 14c. Each frame section 14c comprises radially extending, vertical, side wall members 10, and each frame section is caused to define a plurality of vertically aligned, sector-like drawer spaces by means of horizontal wall members 11, 12 and 13. The horizontal wall members 11, 12 and 13 are provided with flanges along their radial boundaries through which they are suitably secured, as by welding, to the vertical radial wall members 10 of the same frame section. The several frame sections are, or may be, all duplicates of one another, so that a description of one frame section suffices for all.

The bottom wall 11 of each frame section 14c has affixed to the lower face thereof, as by welding, an offset tongue 11b which is adapted to be driven into a space above the platform 14 and below a portion of the sleeve 5. The frame section 14c fits snugly within the flange 14b of the platform or disc 14 when the tongue is driven home, so that the frame section is held firmly and stably in place, but with capacity for removal if removal should be desirable or necessary. This provision for ready application and removal of a cabinet frame section yields an extreme flexibility of arrangement at the option of the user, since any sector may be used to mount a cabinet frame section 14c or may be used as an open bin compartment.

No claim is made herein to the feature of protecting the cabinet section against dislodgment, that subject-matter being disclosed and claimed in my pending application, Serial No. 483,852, filed April 21, 1943, for Cabinets, which is a division hereof.

The wall member 12 divides the frame section 14c into upper and lower sector-like drawer spaces, the upper drawer space being bounded by upper and lower horizontal wall members 13 and 12 and by the radially extending vertical wall members 10, and the lower drawer space being bounded by upper and lower horizontal wall members 12 and 11 and by the radial wall members 10.

Each drawer space is intended and adapted to receive a sector-like drawer 15 which may be slid into and out of the drawer space, and which substantially fits the space when fully inserted in it. Each drawer comprises an inner end wall 16, converging radial side walls 17, an outer arcuate end wall 18, and a bottom wall 19.

Each drawer is desirably divided into a number of separate compartments, the arrangement as illustrated including a pair of trays 20 and 21 whose adjacent walls are spaced apart at their lower ends, but are joined at their upper ends along substantially the middle radius of the drawer. These trays not only provide individual storage compartments themselves, but they divide the drawer space so as to define a number of additional distinct compartments in cooperation with the side and end walls of the drawer. Beyond the inner ends of the trays 20 and 21 a pair of radially extending, flanged partition members 22 and 23 are provided which divide the space lying inward from the trays into right and left-hand compartments. The partition members 22 and 23, like the adjacent walls of the trays 20 and 21 are united to one another at their upper ends, but are spaced apart at their lower ends. The partition members 22 and 23, and the trays 20 and 21 are all fixed in place on the bottom wall of the drawer in any suitable manner as by welding.

It is an important object of the invention to provide for guiding the drawer into and out of its drawer space, without turning, and with the middle radius of the drawer in substantial coincidence with the middle radius of the drawer space. To this end the bottom wall 11 of the lower drawer space has secured to it, as by welding, an L-shaped guide bar 24. The bar comprises a horizontal flange 25 through which the bar is secured by welding to the bottom wall 11 of the cabinet section frame, and a vertical flange 26 which extends upward into the drawer space. The flange 26 constitutes a guiding member for preventing turning of the drawer when it is partially withdrawn from the drawer space, and for

causing the drawer to travel into and out of the drawer space in a radial direction.

The inner end wall 16 of the drawer is formed with a slot 27 for receiving the guiding member 26, and the bottom wall 19 of the drawer is formed with a radial slot 28 in radial alignment with the slot 27 for receiving the guiding member 26. The space provided between the partition members 22 and 23 at their lower ends and between the adjacent walls of the trays 20 and 21 is also for the purpose of accommodating the guiding member 26 and of permitting the guiding member to cooperate with the partition members and with the tray walls, as well as with the slots 27 and 28, for guiding the drawer into and out of the drawer space.

With the arrangement described, it will be apparent that the drawer is always centered with reference to the drawer space, that it has no freedom to turn as it is moved into and out of the drawer space, and that it is always compelled to travel in the direction of the guide member 26, to wit, so that its middle radius is substantially in coincidence with the middle radius of the drawer space.

It is a further important object of the invention to provide simple and efficient, individual locking means for each drawer, and in this connection it is a further feature that the guide member 26 is utilized for locking the drawer in closed position.

The guide member 26 terminates at its inner end a little short of the inner end of the drawer space. A locking lever 30 is secured upon the bottom wall 19 of the drawer and against the lower face thereof by means of a rivet 31, the lever being desirably of substantially the same thickness as the horizontal flange 25 of the angle bar 24. The lower head of the rivet 31 does not protrude below the lower face of the lever 30.

The lever is formed at its inner end with a hook portion 32 which is adapted to lock behind the inner end of the guide member 26 when the drawer is in fully closed position. The hook 32 is disposed a short distance inward beyond the inner end wall 16 of the drawer. The lever 30 is formed at its outer end with a handle portion 33 which extends a short distance outward from the outer arcuate end wall 18 of the drawer in an accessible position, so that the lever may be operated by the handle either to locking or unlocking position, simply by rocking the lever 30 on its pivot 31.

Access to the drawer may be had without affecting any other drawer of the cabinet by operating the lever 30 to unlocking position, seizing the drawer by the drawer handle 34, and pulling it outward along the path defined by the cooperating guide members on the drawer and on the frame.

The upper horizontal wall 12 of the lower drawer space has affixed to it near its outer extremity a downwardly extending lug 35. When the drawer is first put into place, the inner end wall 16 may be worked past this lug by a tilting of the drawer, and a slight bending of the walls 11 and 12. After the drawer has been put into place, the lug 35 cooperates with the inner end wall 16 of the drawer to prevent the drawer from sliding or from being accidentally drawn all the way out of the drawer space.

The construction of the upper drawer and the upper drawer space bounded by the horizontal walls 12 and 13 is identical with that of the lower drawer and drawer space which has been de-

scribed. No further detailed description is, therefore, considered necessary, and corresponding reference characters with the subscript *a* added in each instance have been applied to parts of the upper drawer and upper drawer space which are duplicates of parts already described.

The other cabinet sections and the drawers mounted in them are desirable duplicates of the cabinet section and of the drawers which have been described. Each drawer is guided for radial movement without turning, and each is provided with its own individual locking means. Each cabinet section is secured against dislodgment in the manner already described.

I have described what I believe to be the best embodiment of my invention. I do not wish, however, to be confined to the embodiment shown, but what I desire to cover by Letters Patent is set forth in the appended claims.

I claim:

1. In a cabinet including a cabinet frame comprising upper and lower horizontal walls and converging side vertical walls defining a drawer space, and a drawer slideable into and out of said space, in combination, an elongated drawer guiding member carried on one of the horizontal walls and extending into the drawer space for guiding a drawer into and out of said space, elongated guide means forming part of the drawer and cooperative with said guiding member to guide the sector-like drawer into said space without turning, and a locking lever pivotally mounted on the drawer alongside said guide means, said lever having a latch at the inner end thereof for cooperating with the inner end of the guide member to lock the drawer closed, and a handle at the outer end thereof extending beyond the outer end of the drawer for operating the lever to and from locking position.

2. In a cabinet including a cabinet frame comprising upper and lower horizontal walls and vertical side walls defining a drawer space, in combination, an elongated drawer guiding member carried by the lower horizontal wall and extending part way to the inner boundary of said drawer space for guiding a drawer into and out of said space, a drawer slideable into and out of said space and including an inner end wall and a bottom wall, both formed with slots for accommodating the guide member, and a locking lever pivotally mounted on the lower side of the bottom wall of the drawer and having a latch at the inner end thereof for cooperating with the inner end of the guide member to lock the drawer in closed position, and a handle portion at the outer end thereof beyond the outer boundary of the drawer for operating the lever to and from locking position.

3. In a cabinet including a cabinet frame comprising upper and lower horizontal walls and vertical side walls defining a drawer space, in combination, an elongated drawer guiding member carried by one of the horizontal walls and extending into the drawer space for guiding a drawer into and out of said space, and a drawer slideable into and out of said space, said drawer having an inner end wall formed with a slot for passing the guide member, and spaced longitudinally extending partition members adapted to receive the guiding member between them.

4. In a cabinet including a cabinet frame comprising upper and lower horizontal walls and vertical side walls convergent toward a center point and defining a drawer space, in combination, a radially extending drawer guiding member carried by one of the horizontal walls substantially midway between the side walls and extending into the drawer space for guiding a drawer into and out of said space without turning, and a drawer slideable into and out of said space, said drawer having an inner end wall formed with a slot through which the guiding member may pass, and spaced, radially extending partition members adapted to receive the guiding member between them.

5. In a cabinet including a cabinet frame comprising upper and lower horizontal walls and vertical side walls convergent toward a center point and defining a drawer space, a radially extending drawer guiding member carried by the lower horizontal wall substantially midway between the side walls and extending into the drawer space for guiding a drawer into and out of said space without turning, and a drawer slideable into and out of said space, said drawer having an inner end wall and a bottom wall both provided with slots for receiving the guiding member, and spaced, radially extending partition members adjacent the opposite sides of the slots adapted to receive the guiding member between them.

6. In a cabinet including a cabinet frame comprising upper and lower horizontal walls and converging side vertical walls defining a drawer space, and a drawer slideable into and out of said space, in combination, an elongated drawer guiding member carried on one of the horizontal walls and extending into the drawer space for guiding a drawer into and out of said space, elongated guide means forming part of the drawer and cooperative with said guiding member to guide the drawer into said space without turning, a locking member, and means mounted on the drawer and supporting the locking member in a constantly accessible position with capacity for operative movement relative to the drawer, said locking member being manually operable into and out of locking engagement with the guiding member when the drawer is closed.

7. In a cabinet including a cabinet frame comprising upper and lower horizontal walls and vertical side walls convergent toward a center point and defining a drawer space, and a drawer slideable into and out of said space, in combination, a radially extending guide member on the frame substantially midway between the side walls of said drawer space, radially extending cooperative guiding means on the drawer substantially midway between the side boundaries thereof, and a locking member carried by the drawer and extending beyond the outer end thereof, means supporting the locking member on the drawer for operative movement relative thereto, said locking member cooperative with the guide member on the frame to hold the drawer in closed position, and operable when the drawer is closed to lock and unlock the drawer.

PHILIP ROSENBERG.
